UNITED STATES PATENT OFFICE

WILHELM B. BRONANDER, OF MONTCLAIR, NEW JERSEY, ASSIGNOR TO AMERICAN MACHINE & FOUNDRY COMPANY, A CORPORATION OF NEW JERSEY

CIGARETTE ROD FORMER

Application filed January 13, 1932. Serial No. 586,427.

This invention relates to an improvement in cigarette rod formers for continuous rod cigarette machines, its main object being to compress and form the tobacco before delivering it upon the traveling paper strip. Heretofore the tobacco stream was fed directly from the feed chute onto the paper with the result that the filler tobacco had a rectangular cross-section considerably wider than the cigarette and the action of the filler forming mechanism and tongue was such that the tobacco was too heavily compressed on the under side, thus forming the cigarettes more oval than round. In this invention a pair of endless belts arranged to form a V-shaped trough, travel under the feed chute, collecting the tobacco in approximately pyramidal form and then carry it forward and deposit it onto the cigarette paper strip by merely parting or separating the belts in such a manner that the same belts form a compressor operating to press the tobacco down against the cigarette paper strip, which is necessary for holding down the tobacco while the paper edges are overlapped, thereby obtaining a cigarette rod whose cross-section is nearer to round than that of any former filler making devices. In warping or turning the belts to deliver the tobacco upon the traveling paper strip, the belts exert a progressively increasing downward pressure on the tobacco. In order to secure an even level and pressure at all times, a narrow blade tongue is placed between the open belts which also guides the tobacco under the tongue of the rod forming tube. The narrow blade tongue may be replaced by a compressor wheel, if desired. Another advantage of this invention is that the paper does not pass under the feed for receiving the tobacco, thereby avoiding the trouble of tobacco crumbs catching between the edge of the paper and its guide. A further object is the production of a device capable of making perfect cigarettes at considerably higher speeds than obtainable with prior constructions. With these and other objects not specifically mentioned in view, the invention consists in certain constructions and combinations which will be here-

inafter described and then specifically set forth in the claims hereunto appended.

In the accompanying drawings:

Fig. 1 is a front elevation of the new cigarette rod former; 55

Fig. 2 is a plan view of the same;

Fig. 3 is a longitudinal cross-section of the rod former taken on line 3—3 of Fig. 2;

Fig. 4 is a longitudinal cross-section showing the connection between the carrier belts 60 and the folding tongue;

Fig. 5 is a cross-section of the folding tongue taken on line 5—5 of Fig. 4; and

Figs. 6 to 9 are all cross-sections of the new cigarette rod former taken on lines 6—6, 65 7—7, 8—8 and 9—9 respectively, of Fig. 2.

In carrying the invention into effect there is provided a forming tape for forwarding a cigarette paper strip, a pair of reversely warped endless belts arranged to form a V-shaped trough adapted to receive a shower of tobacco, and a channel having an open bottom to deliver the tobacco onto the cigarette paper strip on said tape and compress it thereon, mechanism for driving and guiding said belts, a rod forming plate supporting said tape and extending under said channel, a tongue cooperating with said plate to fold the cigarette paper strip about the tobacco, and means for compressing the tobacco 80 in said trough. In the best forms of construction contemplated said mechanism includes side guides for the portions of said belts which form said trough and channel, 85 guide plates on said guides engaging the upper edges of the belts, a guide bracket supporting said guides, and pulleys over which said endless belts are trained. In the preferred embodiment the means for compressing the tobacco in said trough includes a bridge to partially compress the tobacco in said trough, and a tongue plate arranged to further partially compress the tobacco in said channel and guide it under said tongue. These various means and parts may be widely varied in construction within the scope 90 of the claims, for the particular device selected to illustrate the invention is but one of many possible concrete embodiments. The invention, therefore, is not to be restricted to 100

the specific construction shown and described.

The new cigarette rod former has two endless belts 15 and 16. Belt 15 is driven from a pulley 17 running over a pulley 18 which is loosely mounted on guide bracket 19 supported by the main frame 20 of the cigarette machine. Pulley 17 is mounted on shaft 21 supported by bearing 22. Shaft 21 carries another pulley 23 which is driven by a belt 24 from the main drive of the cigarette machine. To shaft 21 is furthermore fastened a gear 25 driving a gear 26 on shaft 27 supported by bearing 28. Shaft 27 carries also pulley or roller 29 driving the belt 16 which runs over a pulley 30, also pivoted to bracket 19. Rollers 18 and 30 are so placed that belts 15 and 16 will abut at their lower edges to form a V-shaped trough underneath the tobacco chute 31 which extends partly into the channel, Fig. 6. Pulleys 18 and 30 are assisted in making the V-shaped trough by side guides 32. The belts 15 and 16 are furthermore guided by guide plates 33 mounted on side guides 32 and engaging the upper edges of the belts. Pulleys 17 and 29 are set at different angles than rollers 18 and 30 and are placed in such a manner that belts 15 and 16, formerly forming a V-shaped trough which is closed at the bottom, will be reversely warped or twisted to open up at the bottom and nearly close at the top to form an open bottomed channel, with the result that the tobacco T drops on the traveling paper strip P but is compressed more at the top than at the bottom. This warping or twisting of the belts 15 and 16 creates a downward pressure on the tobacco and so the warping of the belts 15 and 16 makes the same belts which acted as a tobacco carrier 40 also act as a compressor.

The continuously traveling paper strip P is fed from a reel R, having a band B provided with a weight W on its lower end and dragging on periphery of the reel as shown in Figs. 1 and 3, over a guide bar 34 and roller 35 onto the forming tape 36 at pulley 37 pivoted in bracket 38 fastened to the rod forming plate 39 supported by the main frame 20 of the machine. The top of the plate 39 is flat while underlying the bottom of the channel between belts 15 and 16, but after leaving the same plate 39 is provided with a progressively deeper groove which guides the folding tape 36 and this in turn folds the paper P around the filler tobacco T to form a round cigarette rod. A tongue 40 placed over plate 39 shapes the top part of the rod. Tongue 40 equipped with lug 41 is held by guide bars 42 mounted on plate 39. As soon as the paper strip P leaves belts 15 and 16, it starts to curl up and finally forms a round rod. In order to prevent the edges of the paper from being pinched between belt 15 and pulley 17, as well as between belt 16 and pulley 29 as they leave the same, on starting to

fold up the edges of the paper P, the tape 36 is brought slightly downward by inclining the top of the plate 39 downwardly away from the channel between the belts 15 and 16, Fig. 4, thus leaving paper P and tape 36 straight at the high point "A". Paper P and tape 36 run parallel to the lower edges of the belts 15 and 16 while forming the bottom of the channel between said belts.

The tobacco T coming from the feed chute 31 and falling into the V-shaped trough formed by belts 15 and 16 is partially compressed before warping of the belts 15 and 16 by a bridge 43 supported by side guides 32. When the belts start to twist when leaving guide plates 33 the tobacco is still further compressed by a narrow tongue plate 44 and guided into the folding tongue 40. Tongue plate 44 also prevents springy parts of stems, etc., from rising up and stopping the smooth travel of the tobacco. The rear end of the tongue 40 extends partly in between belts 15 and 16 thereby acting as a scraper for the belts 15 and 16 as they pass around the end rolls. As tongue 40 is removable, it is sometimes difficult to place the same in the exact position as before and thereby the scraping action of the rear end is harmed. For this reason a fixed bridge and scraper 45, Fig. 4, can be installed and the removable tongue 40 extended thereon.

By this construction it has been found possible to make perfect cigarettes at considerably higher speeds than on prior known constructions, up to 2,000 cigarettes per minute. With this arrangement of reversely warped belts receiving the showered tobacco and delivering it to the cigarette paper strip on the forming tape supported by the rod forming plate, it has been found that there is no jamming in the rod former, due to breaking of the cigarette rod at these higher speeds as in prior constructions.

What is claimed is:

1. The combination with a forming tape for forwarding a cigarette paper strip, of a pair of reversely warped endless belts, one portion of said belts being inclined downwardly toward each other into abutting relation at their lower edges to form a V-shaped trough and adapted to receive a shower of tobacco, and another portion of said belts being inclined downwardly away from each other to form a channel having an open bottom and to deliver the tobacco to the cigarette paper strip on said tape and compress it thereon, and mechanism for driving and guiding said belts.

2. The combination with a forming tape for forwarding a cigarette paper strip, of a pair of reversely warped endless belts, one portion of said belts being inclined downwardly toward each other into abutting relation at their lower edges to form a V-shaped trough and adapted to receive a shower of

tobacco, and another portion of said belts being inclined downwardly away from each other to form a channel having an open bottom and to deliver the tobacco to the cigarette paper strip on said tape and compress it thereon, and mechanism for driving and guiding said belts, said mechanism including side guides for the portions of said belts forming said trough and channel, and guide plates on said side guides engaging the upper edges of belts along said trough.

3. In a rod former for continuous rod cigarette machines, the combination with a forming tape for forwarding a cigarette paper strip, of a pair of reversely warped endless belts, one portion of said belts being inclined downwardly toward each other into abutting relation at their lower edges to form a V-shaped trough adapted to receive a shower of tobacco, and another portion of said belts being inclined downwardly away from each other to form a channel having an open bottom and to deliver the tobacco to the cigarette paper strip on said forming tape and compress it thereon, mechanism for driving and guiding said endless belts, a rod forming plate supporting said tape and extending under said channel, a tongue cooperating with said plate to fold the cigarette paper strip about the tobacco, and means engaging the tobacco between said belts for compressing the same.

4. In a rod former for continuous rod cigarette machines, the combination with a forming tape for forwarding a cigarette paper strip, of a pair of reversely warped endless belts, one portion of said belts being inclined downwardly toward each other into abutting relation at their lower edges to form a V-shaped trough adapted to receive a shower of tobacco, and another portion of said belts being inclined downwardly away from each other to form a channel having an open bottom and to deliver the tobacco to the cigarette paper strip on said forming tape and compress it thereon, mechanism for driving and guiding said endless belts, a rod forming plate supporting said tape and extending under said channel, a tongue cooperating with said plate to fold the cigarette paper strip about the tobacco, and means engaging the tobacco between said belts for compressing the same, said mechanism including side guides for the portions of said endless belts which form said trough and channel, guide plates on said guides engaging the upper edges of the belts, a guide bracket supporting said guides, and pulleys over which said endless belts are trained.

5. In a rod former for continuous rod cigarette machines, the combination with a forming tape for forwarding a cigarette paper strip, of a pair of reversely warped endless belts, one portion of said belts being inclined downwardly toward each other into abutting

relation at their lower edges to form a V-shaped trough adapted to receive a shower of tobacco, and another portion of said belts being inclined downwardly away from each other to form a channel having an open bottom and to deliver the tobacco to the cigarette paper strip on said forming tape and compress it thereon, mechanism for driving and guiding said endless belts, a rod forming plate supporting said tape and extending under said channel, a tongue cooperating with said plate to fold the cigarette paper strip about the tobacco, and means engaging the tobacco between said belts for compressing the same, the portion of said forming plate underlying said channel having a flat upper surface and the portion of said plate remote from said channel having a concave recess to fold the edges of the cigarette paper strip upwardly about the tobacco.

6. In a rod former for continuous rod cigarette machines, the combination with a forming tape for forwarding a cigarette paper strip of a pair of reversely warped endless belts, one portion of said belts being inclined downwardly toward each other into abutting relation at their lower edges to form a V-shaped trough adapted to receive a shower of tobacco, and another portion of said belts being inclined downwardly away from each other to form a channel having an open bottom and to deliver the tobacco to the cigarette paper strip on said forming tape and compress it thereon, mechanism for driving and guiding said endless belts, a rod forming plate supporting said tape and extending under said channel, a tongue cooperating with said plate to fold the cigarette paper strip about the tobacco, and means engaging the tobacco between said belts for compressing the same, said means for compressing the tobacco including a bridge arranged to compress the tobacco in said trough, and a tongue plate arranged to further compress the tobacco in said channel and guide it under said tongue.

7. In a rod former for continuous rod cigarette machines, the combination with a forming tape for forwarding a cigarette paper strip, of a pair of reversely warped endless belts, one portion of said belts being inclined downwardly toward each other into abutting relation at their lower edges to form a V-shaped trough adapted to receive a shower of tobacco, and another portion of said belts being inclined downwardly away from each other to form a channel having an open bottom and to deliver the tobacco to the cigarette paper strip on said forming tape and compress it thereon, mechanism for driving and guiding said endless belts, a rod forming plate supporting said tape and extending under said channel, a tongue cooperating with said plate to fold the cigarette paper strip about the tobacco, and means

engaging the tobacco between said belts for compressing the same, the top of said forming plate having a flat portion underlying said channel and a progressively deeper reversed portion adapted to fold the edges of the paper strip upwardly about the tobacco, and the top of said forming plate also being inclined downwardly away from said channel to prevent the edges of the paper from being pinched against the lower edges of said endless belts.

8. In a rod former for continuous rod cigarette machines, the combination with a forming tape for forwarding a cigarette paper strip, of a pair of reversely warped endless belts, one portion of said belts being inclined downwardly toward each other into abutting relation at their lower edges to form a V-shaped trough adapted to receive a shower of tobacco, and another portion of said belts being inclined downwardly away from each other to form a channel having an open bottom and to deliver the tobacco to the cigarette paper strip on said forming tape and compress it thereon; mechanism for driving and guiding said endless belts, a rod forming plate supporting said tape and extending under said channel, a tongue cooperating with said plate to fold the cigarette paper strip about the tobacco, and means engaging the tobacco between said belts for compressing the same, one end of said tongue extending inwardly between said endless belts and being shaped to act as a scraper for said belts.

9. In a rod former for continuous rod cigarette machines, the combination with a forming tape for forwarding a cigarette paper strip, of a pair of reversely warped endless belts, one portion of said belts being inclined downwardly toward each other into abutting relation at their lower edges to form a V-shaped trough adapted to receive a shower of tobacco, and another portion of said belts being inclined downwardly away from each other to form a channel having an open bottom and to deliver the tobacco to the cigarette paper strip on said forming tape and compress it thereon; mechanism for driving and guiding said endless belts, a rod forming plate supporting said tape and extending under said channel, a tongue cooperating with said plate to fold the cigarette paper strip about the tobacco, and means engaging the tobacco between said belts for compressing the same, and a fixed bridge and scraper extending between said endless belts and arranged to guide the tobacco under said tongue and adapted to scrape tobacco from said belts.

10. The combination with a forming tape for forwarding a cigarette paper strip, of a pair of endless belts arranged to operate on either side of a stream of tobacco to forward and compress the same, pulleys over which

the forward end of said belts run, and a stationary rod forming tongue coacting with the tape to form the tobacco into a cigarette rod, said rod forming tongue having a rear portion fitting the surfaces of the belts passing over said pulleys to guide tobacco from the belts into the tongue and to prevent stray particles of tobacco from passing on with the belt.

11. The combination with a forming tape for forwarding a cigarette paper strip, of a pair of endless belts arranged to operate on either side of a stream of tobacco to forward and compress the same, pulleys over which the forward end of said belts run, a stationary rod forming tongue coacting with the tape to form the tobacco into a cigarette rod, said rod forming tongue having a rear portion fitting the surfaces of the belts passing over said pulleys to guide tobacco from the belts into the tongue and to prevent stray particles of tobacco from passing on with the belt, said rear portion of the tongue being made separate from the forward portion of the tongue, and means for removably supporting the forward portion and immovably securing the rear portion whereby the forward portion can be readily removed without disturbing the relationship between said rear portion and the belts.

12. The combination with a forming tape for forwarding the cigarette paper strip, of a pair of vertically inclined endless belts adapted to operate on either side of a stream of tobacco to forward the same, pulleys over which said belts are run, means coacting with the tape to form the paper and tobacco into a cigarette rod, and a tobacco guiding element positioned to engage the upper side of said stream having portions operating on the surfaces of the belts as they pass around the pulleys to scrape particles of tobacco from the belts.

13. The combination with a device for guiding showered tobacco, of a pair of belts, mechanism for guiding said belts in V formation under said device to receive and forward tobacco therefrom, means for separating the lower edges of said belts beyond said source while the belts continue to move in substantially the same direction, devices for moving a cigarette paper strip under said belts to receive the tobacco where said belts separate, and means for forming the strip and tobacco thereon into a cigarette rod.

14. The combination with a device for guiding showered tobacco, of a pair of belts, mechanism for guiding said belts in V formation under said device to receive and forward tobacco therefrom, means for separating the lower edges of said belts beyond said device while the belts continue to move in substantially the same direction, means for moving a cigarette paper strip under said belts to receive the tobacco where said belts separate,

- and means for forming the strip and tobacco thereon into a cigarette rod, said paper moving means including means bringing the paper against the lower edges of the belts 5 at a point beyond said device.
15. The combination with a chute for guiding showered tobacco, of a pair of belts, mechanism for guiding said belts in V formation under said chute with their lower edges 10 together to receive and forward tobacco, belt guiding means to warp at least one of said belts towards a vertical position to separate the lower edges of said belts, a web passing along and under said belts at the position 15 where the edges part for forwarding the tobacco, and a rod forming tongue cooperating directly with the tobacco as it passes from between said belts for forming the tobacco into a cigarette rod.
20. 16. The combination with a chute for guiding showered tobacco, of a pair of belts, mechanism for guiding runs of said belts in V formation under said chute with their lower edges together to receive and forward 25 tobacco, belt guiding means to warp at least one of said belts towards a vertical position to separate the lower edges of said belts, means extending under said belts at the position where the edges part for forwarding 30 the tobacco, and means cooperating with said receiving means for forming the tobacco on said forwarding means into a cigarette rod, said warping means comprising a pulley over which one of said belts runs having its axis 35 at an angle to the plane of the belts as they pass under the chute.
17. The combination with a chute for guiding showered tobacco, of a pair of belts, mechanism for guiding said belts in V formation under said chute with their lower edges together to receive and forward tobacco, belt guiding means to warp at least one of said belts towards a vertical position to separate the lower edges of said belts, 40 means extending under said belts at the position where the edges part for forwarding the tobacco, and means cooperating with said receiving means for forming the tobacco on said forwarding means into a cigarette rod, said mechanism including V shaped 45 guide means having an apex angle of less than a right angle for maintaining the belts in predetermined V relationship under the chute.
50. 18. The combination with a chute for guiding showered tobacco, of mechanism passing under said chute for receiving and forwarding the showered tobacco in a continuous 55 stream, mechanism receiving tobacco from said forwarding means and forming the same into a cigarette rod, and a stationary strip of a thickness substantially less than the width of the stream of forwarded tobacco 60 extending downwardly and along the upper 65
- side of said stream to compress the central portion only thereof.
19. In a cigarette machine, the combination with a tobacco feed chute, of a pair of belts, mechanism for guiding said belts in V formation under said chute to receive and forward tobacco therefrom, means beyond said chute for separating the lower edges of said belt, devices for feeding a paper strip under said belts at a position between the said chute and the separating means and thence along the belts to receive tobacco deposited as a result of the separating, and means for forming the strip and tobacco thereon into a cigarette rod. 70 75 80
20. In a cigarette machine, the combination with a tobacco feed chute, of a pair of belts, mechanism for guiding said belts in V formation under said chute to receive and forward tobacco therefrom, means beyond said chute for separating the lower edges of said belt, and devices for feeding a paper strip under said belts to receive tobacco deposited as a result of the separating of the 85 belts and tobacco compressing means acting on the upper side of the tobacco stream where the belt edges are separated to compress the tobacco against said paper strip. 90
21. In a cigarette machine, the combination with a tobacco feed chute, of a pair of belts, mechanism for guiding said belts in V formation under said chute to receive and forward tobacco therefrom, means beyond said chute for separating the lower edges of said belt, devices for feeding a paper strip under said belts to receive tobacco deposited as a result of the separating of the belts, tobacco compressing means acting on the upper side of the tobacco stream where the 95 belt edges are separated to compress the tobacco against said paper strip, and rod forming means including a rod forming element arched over the tobacco and extending between the exit ends of said belts, 100 said compressing means having a portion extending under the rear end of said element. 105 110
